Primary Examiner—Charles A. Rademaker

(74) Attorney, Agent, or Firm—Morriss O'Bryant Compagni, P.C.

CLAIM

The ornamental design for a paper trimmer blade holder, as shown and described.

DESCRIPTION

FIG. 1 is a top perspective top view of a paper trimmer blade holder showing our new design;

FIG. 2 is a top plan view thereof;

FIG. 3 is a bottom plan view thereof;

FIG. 4 is a front plan view thereof;

FIG. 5 is a rear plan view thereof;

FIG. 6 is a right end elevation thereof; and,

FIG. 7 is a left end elevation thereof.

The broken line showing of environment is for illustrative purposes only and form no part of the claimed design.
